CLAIM

The ornamental design for stand up paddleboard as shown and described.

DESCRIPTION

FIG. 1.1 shows a stand up paddleboard.

FIG. 1.2 is a back view thereof;

FIG. 1.3 is a top view thereof;

FIG. 1.4 is a bottom view thereof;

FIG. 1.5 is a left view thereof;

FIG. 1.6 is a right view thereof;

FIG. 1.7 is a perspective view thereof.

FIG. 4.1 is a front view of a first part of the stand up paddleboard of FIG. 1.1 shown in isolation for clarity of illustration.

FIG. 4.2 is a back view thereof;

FIG. 4.3 is a top view thereof;

FIG. 4.4 is a bottom view thereof;

FIG. 4.5 is a left view thereof;

FIG. 4.6 is a right view thereof;

FIG. 4.7 is a perspective view thereof.

FIG. 7.1 is a front view of a second inner part of the stand up paddleboard of FIG. 1.1 shown in isolation for clarity of illustration.

FIG. 7.2 is a back view thereof;

FIG. 7.3 is a top view thereof;

FIG. 7.4 is a bottom view thereof;

FIG. 7.5 is a left view thereof;

FIG. 7.6 is a right view thereof;

FIG. 7.7 is a perspective view thereof.

The broken line showing of the stand up paddleboard is for the purpose of illustrating portions of the article that forms no part of the claimed design.

1 Claim, 8 Drawing Sheets
